UNITED STATES PATENT OFFICE.

NICHOLAS JENKINS, OF WATERBURY, CONNECTICUT, ASSIGNOR TO HOLMES, BOOTH & HAYDENS, OF SAME PLACE.

STAND-LAMP.

SPECIFICATION forming part of Letters Patent No. 320,476, dated June 23, 1885.

Application filed March 2, 1885. (No model.)

To all whom it may concern:

Be it known that I, NICHOLAS JENKINS, of Waterbury, county of New Haven, and State of Connecticut, have invented a new and useful 5 Improvement in Stand-Lamps, of which the following is a specification.

My improvement relates to lamp-reservoirs made of metal.

The object of my improvement is to provide 10 a simple and ornamental means whereby pendants may be supported around the reservoirs.

The improvement consists in a new article 15 of manufacture composing the following elements, to wit: A metal reservoir having a cylindric middle portion and an inwardly-extending lower portion, a band of metal secured to the cylindric portion, extending below the cylindric portion around the inwardly-extending lower portion, and provided with perforations below the cylindric portion for the 20 reception of the hooks or analogous fastenings of pendants.

The accompanying drawing is a partly sectional side view of a lamp embodying my improvement.

A designates the pedestal of the lamp, which may be of any desirable construction.

B designates an oil-reservoir, made of metal. It is supported by the pedestal A, and between 30 it and the pedestal are arranged a drip-cup, C, and a perforated air-distributer, D.

E designates the burner-tube, which, as here shown, is of the Argand type, although its form is immaterial so far as the present improvement is concerned. It is provided with 35 wick-adjusting mechanism *a*, with an air-distributer, *b*, and deflectors *c d*. The reservoir B has at the middle an externally-cylindric portion, *e*. Below this cylindric portion *e* the 40 reservoir extends or recedes inwardly.

G designates a band of metal arranged around the cylindric portion *e* of the reservoir and secured thereto by solder or otherwise. It may be ornamented to suit the taste. Its configuration may, however, be varied. Close to the lower edge are perforations *f*. These perforations are below the cylindric portion *e* of the reservoir and opposite the inwardly-extending lower portion.

By combining with a reservoir having a cylindric portion and an inwardly-extending lower portion a strip depending below the cylindric portion of the reservoir, and providing said strip with perforations below the cylindric portion of the reservoir, I provide a space between the perforated portion of the strip and the reservoir which will accommodate hooks or other fastenings of pendants without entailing the contact thereof with the reservoir; hence provision for a free adjustment of the pendants is afforded.

What I claim as my invention, and desire to secure by Letters Patent, is—

A new article of manufacture, comprising 65 the following elements, to wit: a metal reservoir having an externally-cylindric portion and an inwardly extending or receding lower portion, and a strip secured to the cylindric portion extending below the cylindric portion 70 and provided below the cylindric portion and opposite the inwardly-extending portion of the reservoir with perforations for receiving hooks or fastenings of pendants.

NICHOLAS JENKINS.
